[57] CLAIM

The ornamental design for a study carrel, as shown and described.

DESCRIPTION

FIG. 1 is a perspective view of a study carrel showing my new design, the opposite side being a mirror image thereof;

FIG. 2 is a top plan view thereof;

FIG. 3 is a front elevational view thereof;

FIG. 4 is a side view, the opposite side being a mirror image thereof;

FIG. 5 is a rear elevational view thereof;

FIG. 6 is a perspective view of a modified form of the study carrel shown in FIG. 1, the opposite side being a mirror image thereof;

FIG. 7 is a top plan view thereof;

FIG. 8 is a front elevational view, the rear being identical thereto; and,

FIG. 9 is a side elevational view, the opposite side being identical thereto.
